ELECTRICAL PULSE REGULATOR

Norman H. Milde, Torrance, Calif.

Application October 29, 1946, Serial No. 706,496

5 Claims. (Cl. 177—380)

(Granted under the act of March 3, 1883, as
amended April 30, 1928; 370 O. G. 757)

1

The invention described herein may be manufactured by or for the United States Government for governmental purposes without payment to me of any royalty thereon.

The present invention relates to an electrical pulse regulator, and the invention is adapted for use wherever it is desired to provide an electrical signal of predetermined duration and intensity.

The principal object of the invention is to provide an electrical timing circuit capable of producing a signal of definite and predetermined duration, regardless of the duration of the circuit initiating signal.

In releasing bombs from aircraft it is currently possible to initiate the bomb release sequence or operation by several different control devices each of which may provide an electrical pulse, or impulse, of different duration and possibly of different electrical characteristics. However for proper operation of the bomb release circuit it is highly desirable that a pulse of definite duration and strength be provided. Thus it is a further object of the invention to provide an improved bomb release circuit or system including a timing circuit or regulator intermediate of the bomb release initiating means and the bomb release devices capable of delivering a signal of predetermined duration in response to an initiating impulse of variable and unpredictable duration.

Another object of the invention is to provide a combination of magnetic and time delay relays connected into a common circuit and adapted to produce an electrical impulse of definite duration in response to initiating signals of irregular and indefinite duration.

A further object of the invention is to generally improve the construction and arrangement of bomb release circuits, and to provide an improved electrical timing circuit having general applications as well as a particular application in controlling bomb release circuits.

The above and other objects will become apparent on reading the following specification and claims in conjunction with the accompanying drawing, in which:

Fig. 1 is a schematic wiring diagram of a complete bomb release circuit embodying the electrical pulse regulator of the present invention.

Fig. 2 is a wiring diagram of the electrical pulse regulator forming one unit of the bomb release circuit shown in Fig. 1.

Referring to Fig. 1 there is shown diagrammatically a pair of bomb racks 1 and 2 which may be considered as installed in an aircraft on opposite sides thereof, so that rack 1 is on the

2

right side and rack 2 is on the left side of the aircraft. For each bomb carried in the racks there is a solenoid and trip mechanism 3 on the respective racks to provide independent release means for each bomb. Each of the solenoid and trip mechanisms 3 is connected by electrical cables to a rack selector unit 4 which is adapted to automatically operate the bomb trip mechanisms in a preselected sequence. For instance, 10 it is common practice to connect the trip mechanisms to the selector in such manner as to cause release of bombs from opposite sides of the aircraft alternately and thus keep the craft in proper trim or balance. In order to provide pre- 15 determined and uniform time intervals between the dropping of each bomb, release signals are fed to the rack selector unit 4 through a bomb release interval control unit or intervalometer 5 which includes manual control means capable of 20 being set in accordance with the ground speed of the aircraft and the desired spacing of bombs to produce impulses which act on the rack selector unit 4 to give a desired bombing pattern. The bomb release system includes a control panel 25 6 having a pair of switches 7 and 7' and also signal lights as at 8 to indicate the release of each individual bomb. The switch 7 has two separate "on" positions providing circuits whereby the hand-grip push button switch 9 is connected for 30 releasing the bombs one at a time manually or for releasing the bombs in a train upon actuation of the push button. When the "train" setting is used the bombs will fall in a predetermined pattern according to the setting of the bomb re- 35 lease interval control unit 5 and the connections as made between the rack selector unit 4 and the bomb trip mechanisms 3. The switch 7', which merely has "on" and "off" positions, is for the purpose of simultaneously releasing all the bombs in a salvo.

The bomb release circuit and apparatus as described in the preceding paragraph may be initiated or set in motion by electrical impulses from various sources such as the push button 45 bomb release switch 9, by the automatic bomb sight 10 or by a radio signal picked up by the radio receiver 11 on the aircraft. The bomb sight 10 includes an automatic switch adapted to close when a preset contact member is engaged by a 50 motor driven pick-up arm synchronized by the bombardier when the target is initially sighted. Closing the bomb sight automatic switch or the bomb release switch 9 completes a circuit from a source of potential to the input terminal A of 55 the electrical pulse regulator 12, which terminal

may also be connected to the output of radio receiver 11. The radio receiver is mostly used in formation flights in which the leading aircraft is equipped to send out a radio signal for triggering the bomb release systems of the other aircraft in the formation.

In the present invention direct actuation of the interval control unit, rack selector and bomb trip mechanisms by the bomb release initiating means is avoided because these various types of initiating signals are not of uniform and predetermined duration. Instead the electrical pulse regulator 12 receives the bomb release initiating signal at input terminal A and delivers a regulated impulse at output terminal C connected to the interval control unit 5. The interval control unit which may vary in design considerably is dependent for proper operation on receiving an initiating pulse of definite and predetermined duration. For instance the interval control unit may comprise a timing circuit which includes a condenser and resistor network capable of storing a charge and then releasing the charge in spaced surges through a relay for actuation of the rack selector and bomb trip mechanisms. Alternatively this timing circuit or intervalometer may include a vacuum tube or a gas-filled tube such as a Thyratron, or the circuit may include an electro-mechanical timer set in motion by a relay-actuated motor. In any event the successful operation of the interval control unit or intervalometer depends on the input pulse being of definite duration, the length of which will be predetermined within close limits by the design of the interval control unit which it is desired to use. While the duration of the impulse may accordingly vary considerably the range required with interval control units now commonly used is about 0.05 to 0.1 second, and the components of the pulse regulator 12 may be chosen to provide an output impulse having an exact duration which will fall somewhere within this range. Even though the present electrical pulse regulator 12 provides an output of a definite duration it is adapted to be set in operation or "triggered" by various bomb release initiating means such as the bomb release switch 9, the automatic bomb sight 10 or the radio receiver 11. While the duration of the output pulse will usually fall within the above stated time range it should be understood that the invention is in no way limited to providing an impulse of any fixed duration or range, since the time range given is merely stated by way of example.

The electrical pulse regulator 12 indicated in Fig. 1 as forming part of the bomb release system is shown in detail in Fig. 2. The principal components of the regulator are the magnetic relay RE-1, the magnetic relay RE-2, the time delay relay RE-3 and the on-off switch 13. A source of potential such as the battery 14 is connected to the ground terminal B and also to the switch 13 as shown. This source of electrical potential will always determine the electrical characteristics of the output pulse of the regulator 12, and may be designed or selected accordingly with this feature in mind. The relay RE-1 may be termed the input relay and the relay RE-3 may be termed the output relay because of their relative positions and purposes, as will be seen.

The magnetic relay RE-1 includes a holding coil or operating coil 15 which may be energized to move the relay contactor 16 downward against the force of a tension spring 17 and thus break the circuit through contact 18 leading to the holding coil 19 of relay RE-2. The initiating impulse to

the circuit is through the terminal A, through the holding coil 15 and thence to the ground terminal B, it being understood that the ground forms one conductor from the source of the initiating impulse. The initiating impulse regardless of its duration will actuate the relay RE-1 thus breaking the circuit from relay contactor 16 to the coil 19 of relay RE-2. The impulse also energizes holding coil or operating coil 20 of relay RE-2 through contact 21 and auxiliary contactor 22 of the same relay, thus moving the main relay contactors 23, 24 and 25 downwardly against the action of a tension spring 26 to close three circuits at the same time.

Energizing the relay RE-2 to move the contactors downwardly causes contactor 23 to close a circuit through the auxiliary contactor 22 to lock in the holding coil 20 by using the potential source 14. As the contactor 23 is pulled down it first contacts the auxiliary contactor 22 to close the relay lock-in circuit and then moves the contactor 22 downward against the action of the compression spring 22' far enough to break the circuit from the input terminal A to the holding coil 20. Thus it is clear that the auxiliary contactor 22 is operated only by the contactor 23 and not directly by the relay holding coils. This type of relay is usually known as a make-before-break relay, and may include various mechanical arrangements for effecting the desired result. The relay contactor 24 closes a circuit from the potential source 14 to the output terminal C by way of the contact 27, contactor 29 of time delay relay RE-3 and contact 30 of the latter relay. The other terminal of the battery 14 being grounded, the impulse circuit to the interval control unit 5 is completed by means of a ground connection made thereto. The output impulse of the circuit is thus started by closing the contactor 24 on its contact 27 and the electrical characteristics of the impulse is determined by the type of battery or potential source 14 which is used. The contactor 25 completes a circuit from the battery or potential source 14 to the coil 32 of the time delay relay RE-3, the contactor 25 completing its circuit through contact 28.

The time delay relay RE-3 actually governs the duration of the output pulse delivered by the relay system which forms the electrical pulse regulator. Obviously various types of relays may be used depending on the pulse duration desired. For instance the hot wire type or the bimetallic thermal strip type are relatively slow acting, while the dashpot type or the copper slug type are usually much faster. In the present embodiment the copper slug relay RE-3 is illustrated and is preferred in the bomb release system of Fig. 1 for its reliability and its relative quick action. This type of relay is useful only with direct current but the system of Fig. 1 usually depends for power on storage batteries carried by the aircraft. The delayed action of this relay is due to the slow build-up of magnetic flux in the iron core element 33 caused by the hysteresis effect of the copper slugs or washers 34 placed between the coil 32 and the relay contactor 29. When current is turned on in the coil 32 a heavy current is momentarily induced in the copper slugs as the lines of flux cut the slugs. This acts to delay the building up of magnetic flux in the portion of the core 33 nearer to the contactor 29, since the slugs act to absorb the magnetic flux formed by the coil 32. This hysteresis effect dies out as the direct current flowing reaches a steady state, and the core 33 then attracts the contactor 29 which

thus breaks the circuit through contact 30 to terminate the output pulse of the relay system. The copper slugs may be of various thicknesses and may be reduced in number also. A relay which was designed for this same circuit had only one slug having a thickness almost equal to the space taken up by the windings of coil 32. The design of the relay will determine the speed with which it acts but in general the copper slug type of relay is used for time delays of 0.1 second or less. The coil and slug structure of the relay may be termed a timing element, since it determines the time delay characteristic of the relay RE-3.

When the relay RE-3 acts to move the contactor 29 to the left against the force of tension spring 35 the contactor engages contact 31, which is connected to the contactor 16 of relay RE-1. At such time as the initiating current for the relay circuit is cut off, the holding coil 15 of relay RE-1 is deenergized and therefore the contactor 16 moves upwardly to close a circuit from the battery 14 through contactor 24 and contact 27 of relay RE-2, through contactor 29 and contact 31 of relay RE-3, and thence through contactor 16 and contact 18 of the relay RE-1 to the coil 19 of relay RE-2. Since the coil 19 is provided with more turns than coil 20 and since it acts on the relay RE-2 in a direction opposite to that of coil 20 the relay contactors 23, 24 and 25 are immediately forced upwardly. Moving the contactor 23 upwardly breaks the lock-in circuit of holding coil 20 and also allows the auxiliary contactor 22 to again close the line between the holding coil 20 and the relay input terminal A. Moving the contactor 24 upwardly breaks the circuit to the coil 19 from the battery 14, and moving contactor 25 upwardly breaks the circuit from the battery to the coil 32 of the time delay relay RE-3. The springs 26 and 35 act to hold the contactors of the relays RE-2 and RE-3 in the deenergized positions, as shown in Fig. 2. Thus it is seen that the relay system recycles as soon as the initiating pulse terminates, assuming that the relay RE-3 has had time to break the output circuit to output terminal C and move the contactor 23 into engagement with the contact 31. Recycling, which may be defined as restoration of the relays to their original deenergized positions, is thus complete when the time delay relay RE-3 has its contactor 29 restored to its original position of engagement with contact 30, upon breaking of the circuit to coil 32 through contactor 25 of relay RE-2.

If the initiating pulse of the relay system is of shorter duration than the output pulse then the contactor 16 of the relay RE-1 will move upwardly before the contactor 29 of relay RE-3 has had time to engage the contact 31. In this event recycling of the relays will not start until the relay RE-3 has acted to break the output circuit through contact 30 and make its other or recycling circuit by engagement of the contactor 29 and the contact 31. To summarize these operations it might be stated that the relay recycling takes place when the initiating pulse terminates if the output pulse has ceased. Conversely immediate recycling takes place at the end of the output pulse if the initiating pulse has stopped.

By means of the relay system as described above a dependable electrical pulse regulator is provided. The system includes only one variable that affects the pulse duration and that is the time delay relay which must be chosen for the

pulse duration desired. The obvious advantages recommend the relay system for general uses as well as in a bomb release system as described above. The relay system disclosed is particularly unique in its ability to produce an electrical impulse of uniform duration regardless of the length of the initiating impulse applied thereto; and its ability to produce only one such impulse even though the initiating impulse persists indefinitely.

The embodiments of the invention herein shown and described are to be regarded as illustrative only and it is to be understood that the invention is susceptible to variations, modifications and changes within the scope of the appended claims.

I claim:

1. An electrical pulse regulator for connection in an electrical bomb release system between a system initiating means and a bomb release intervalometer, said regulator comprising a magnetic relay having contactors adapted to be actuated in one direction by means of an input pulse of indeterminate duration, a time delay relay including a timing element and including means to connect a constant source of electrical potential to the output terminals of the pulse regulator when said magnetic relay contactors are actuated in said one direction, means included in said magnetic relay to complete a circuit to the timing element of said time delay relay when said contactors are actuated in said one direction whereby the potential supplied to said output terminals is cut off when said timing element acts to energize said time delay relay, means actuated in response to termination of said input pulse after said time delay relay has been energized to actuate said contactors in the opposite direction and thus break the circuit to the timing element of said time delay relay.
2. An electrical pulse regulator for connection in an electrical bomb release system between a system initiating means and a bomb release intervalometer, said regulator comprising an input relay adapted to be energized by an input signal of indefinite duration, a second relay having contactors adapted to be actuated in two directions, means responsive to said input signal to actuate said contactors in one direction, a third relay including a timing element to provide a definite time delay before energization, said third relay including means adapted to connect a constant source of electrical potential to the output terminals of the pulse regulator when said contactors are actuated in said one direction, means included in said second relay to complete a circuit to the timing element of said third relay when said contactors are actuated in said one direction, whereby the potential supplied to said output terminals is cut off when said timing element acts to energize said third relay, means included in said third relay to complete a circuit through said input relay when said input signal terminates and after said third relay has been energized, and means included in said latter circuit to actuate said second relay contactors in the other direction to break the circuit to said timing element and thus deenergize said third relay.
3. An electrical pulse regulator comprising, a magnetic relay having a plurality of contactors adapted to be actuated in two directions, means responsive to an input signal to actuate said contactors in one direction, a time delay relay having a timing element and including means to connect a constant source of electrical potential

to the output terminals of the pulse regulator through one of said contactors when said contactors are actuated in said one direction, another of said contactors being adapted to complete a circuit to said timing element when said contactors are actuated in said one direction, energization of said time delay relay by action of said timing element being adapted to break the circuit to said output terminals and to complete another circuit for recycling said relays upon termination of said input signal, and means for recycling said relays including means adapted to actuate said contactors in the other of said directions.

4. An electrical pulse regulator for connection in an electrical bomb release system between a system initiating means and a bomb release intervalometer adapted to supply a series of time-spaced electrical signals to the bomb trip mechanisms of said system, said regulator comprising an input relay adapted to be energized by an input signal from said system initiating means, a time delay relay having an energizing means and being adapted to complete separate circuits through a movable contactor thereof in both the unenergized and the energized positions of the contactor, a magnetic relay responsive to said input signal for completing the unenergized circuit of said time delay relay to the output terminals of the pulse regulator through a constant potential source and the time delay relay contactor, and for energizing said time delay relay after a predetermined time delay period which determines the duration of the output pulse of the pulse regulator, a relay recycling means to restore the relays to their original unenergized positions, energization of said time delay relay after said time delay period being operative to open the circuit to said output terminals and close a circuit through said time delay relay contactor, said input relay and said potential source to said relay recycling means after termination of said input signal, thus recycling said relays and breaking the circuits originally completed by said magnetic relay in response to said input signal.

5. An electrical pulse regulator for connection in an electrical bomb release system between a system initiating means and a bomb release intervalometer adapted to supply a series of time-

5 spaced electrical signals to the bomb trip mechanisms of said system, said regulator comprising an input relay adapted to be energized by an input signal from said system initiating means, a second relay having contactors adapted to be actuated in two directions, a first electro-magnetic means forming part of said second relay responsive to energization by said input signal to actuate said contactors in one direction, a time delay relay having an energizing means and being adapted to complete separate circuits through a movable contactor thereof in both the unenergized and the energized positions of the contactor, actuation of said second relay contactors in said one direction being operative to complete a circuit to the time delay relay energizing means, to the output terminals of the pulse regulator through a constant potential source and the time delay relay contactor, and to said first 10 electro-magnetic means through said potential source, energization of said time delay relay after a predetermined time delay period being operative to open the circuit to said output terminals and close a circuit through said time delay relay contactor, said input relay and said potential source to a second electro-magnetic means forming part of said second relay after termination of said input signal, said second electro-magnetic means acting in opposition to said first electro-magnetic means and being adapted to overpower said first electro-magnetic means to actuate said second relay contactors in the other direction, thus breaking the circuits originally completed by said latter contactors and recycling the relays of said pulse regulator.
